UNITED STATES PATENT OFFICE.

GEORGE WESLEY MILLER, OF CLARINDA, IOWA.

ATTACHMENT FOR WINDMILLS.

SPECIFICATION forming part of Letters Patent No. 337,421, dated March 9, 1886.

Application filed November 18, 1885. Serial No. 182,730. (No model.)

To all whom it may concern:

Be it known that I, GEORGE WESLEY MILLER, a citizen of the United States, residing at Clarinda, in the county of Page and State of Iowa, have invented a new and useful Improvement in Attachments for Windmills, of which the following is a specification, reference being had to the accompanying drawing.

This invention relates to attachments for windmills for throwing the wheel into and out of operation, and its object is to provide mechanism possessing superior advantages in simplicity, convenience, and general efficiency, by which the wheel will be automatically thrown into and out of operation by a float in a tank, and the water in the latter will be automatically kept at the same level.

This invention is an improvement on that for which Letters Patent of the United States 20 were granted to me January 15, 1884, No. 292,030.

The accompanying drawing is a perspective view of a machine embodying my invention. A represents a portion of the tower or framework of a windmill, on the upper end of which is secured a wind-wheel, which may be of any preferred construction, but which is not here shown, as it forms no part of this invention. The wheel will be provided with mechanism 30 by means of which it may be thrown out of the wind, said mechanism being controlled by a cord, B. To the lower end of this cord is attached a bar, C, which is provided on its outer edge with ratchet-teeth, and which slides 35 on a stanchion, D, in the tower, and is kept in place on said stanchion by means of guideways E.

F represents the pump or plunger rod which is connected with the crank-wheel of the windmill, and which reciprocates vertically when the windmill is rotated in the usual well-known way.

A rock-lever, G, is fulcrumed to the lower end of the stanchion D, and the outer end of 45 said lever is connected or pivoted to the pump-rod F, as shown. To the inner end of this lever is pivoted a pawl, H, which is maintained in a substantially vertical position normally, and has outwardly-extending parallel arms h, 50 which extend on opposite sides of the ratchet-bar C and the stanchion D, so as to guide the

lower end of the said ratchet-bar, and on the outer ends of these arms are secured weights h'. In between the guideways E is pivoted a downwardly-extending detent, I, which is 55 provided with a right-angled weighted arm, K.

L represents a lever, which is pivoted at its upper end to the outer end of the guideway E, and is connected to the free ends of the detent and the pawl by means of cords M.

N represents a sheave that is journaled to a bracket projecting from the stanchion D, and over which passes a cord, O. A weight, P, is attached to one end of this cord, and the cord is also connected to the lower free end of the lever L, and from thence passes through a bracket-eye, R, the outer lower end of the cord being attached to a float, S, in a tank, T. This tank is kept supplied with water from a pump or other water-elevator operated by the 7c windmill.

The operation of my invention is as follows: When the water is at a certain predetermined level in the tank, the float draws upon the cord O and moves the lever L outwardly, which 75 keeps the free ends of the detent and the pawl out of engagement with the ratchet-teeth of the bar C. The pawl H, being connected with the reciprocating plunger-rod by the lever G, moves continually up and down while the 80 wind-wheel is in operation. When the water rises in the tank above the required lever, the float is raised, which slackens on the cord O and causes the weight P to draw the lever L toward the pump-rod, and permits the detent 85 and the pawl to engage with the ratchet-bar. The continuous reciprocating movement of the pawl on the teeth of the ratchet-bar draws the said bar downwardly, as will be readily understood, and the detent, by engaging with said 90 teeth, holds the ratchet-bar in the lowered position. As the bar is drawn downward it exerts a pull on the cord B and causes the wind-wheel to be thrown out of the wind, and thereby causes the pump to cease to operate, thus 95 preventing the water from overflowing the tank and being wasted.

Having described my invention, I claim—

1. The combination of the movable ratchet-bar, the reciprocating plunger-rod, the detent 100 for engaging with the ratchet-bar, the pawl connected to the plunger-rod and reciprocated

thereby, and the lever L, connected to the free ends of the detent and the pawl to keep the latter normally out of engagement with the ratchet-bar, substantially as described.

5 2. The combination of the ratchet-bar, the detent for engaging therewith, the reciprocating plunger-rod, the pawl connected therewith and reciprocated thereby, the lever L, connected with the free ends of the pawl and the 10 detent, and the float connected to said lever, whereby the pawl and detent will engage with the ratchet-bar to move the latter when the float rises, and will release the ratchet-bar when the float descends, substantially as de- 15 scribed.

3. The combination of the movable ratchet-bar, to which the cord B is attached, for throwing the wheel out of or into the wind, the detent for engaging with the said ratchet-bar, the 20 reciprocating plunger-rod, the pivoted lever G, connected to the said rod, the pawl connected to the lever G and operated thereby, the lever L, connected to the pawl and detent, and the 25 float connected to the said lever L, for the purpose set forth, substantially as described.

4. The cord or chain B, connecting with the wind-wheel, in combination with the pitman or plunger F, the movable ratchet-bar C on the end of cord B, the pawl H, engaging therewith, the lever G, connecting the pawl with the 30 plunger, and a float connecting with the pawl, as set forth.

5. The chain or cord B, connecting with the wind-wheel, in combination with the pitman or plunger F, the movable ratchet-bar C on 35 the end of the cord, the pawl H, to engage the ratchet-bar, the float to keep the pawl in engagement when it ascends and force the pawl out of engagement when the float descends, the said plunger or pitman connecting with the 40 pawl, for the purpose set forth.

In testimony that I claim the foregoing as my own I have hereto affixed my signature in presence of two witnesses.

GEORGE WESLEY MILLER.
